US00D940558S

(12) **United States Design Patent** (10) **Patent No.:** **US D940,558 S**
(45) **Date of Patent:** **** Jan. 11, 2022**

(54) **BOTTLE**

(71) Applicant: **AIR UP GROUP GMBH**, Munich (DE)

(72) Inventor: **Magdalena Jüngst**, Munich (DE)

(73) Assignee: **air up group GmbH**, Munich (DE)

(**) Term: **15 Years**

(21) Appl. No.: **29/737,755**

(22) Filed: **Jun. 11, 2020**

Related U.S. Application Data

(62) Division of application No. 35/506,540, filed on Jan. 10, 2019 (U.S. filing date under 35 U.S.C. 384), and having an international filing date of Jan. 10, 2019, now Pat. No. Des. 905,558.

(57) **CLAIM**

The ornamental design for a bottle, as shown and described.

DESCRIPTION

FIG. 1 is a front view of a bottle showing my new design in an assembled configuration;

FIG. 2 is a front perspective view thereof;

FIG. 3 is a top view thereof;

FIG. 4 is an exploded front view thereof showing my new design in a disassembled configuration;

FIG. 5 is a front perspective view thereof; and,

FIG. 6 is a top view thereof.

The broken lines in the figures illustrate portions of the bottle that form no part of the claimed design.

Views of the bottle not shown form no part of the claimed design.

1 Claim, 6 Drawing Sheets
